UNITED STATES PATENT OFFICE.

JOHN J. CASEY, OF GLOUCESTER, MASSACHUSETTS, ASSIGNOR TO KANT CLOG SPECIALTY COMPANY, A CORPORATION OF MASSACHUSETTS.

STRAINER FOR GASOLINE.

Application filed June 7, 1922. Serial No. 566,637.

To all whom it may concern:

Be it known that I, JOHN J. CASEY, a citizen of the United States, residing at Gloucester, in the county of Essex and 5 State of Massachusetts, have invented certain new and useful Improvements in Strainers for Gasoline, of which the following is a specification, reference being had therein to the accompanying drawing.

10 My invention relates to strainers, and has special reference to such strainers as are used on gasoline lines and the like. It has for its object the production of an improved device of this class which will not clog, 15 which may be used in either a horizontal or a vertical position, and which may be easily taken apart and the strainers removed for cleansing or other purposes. Other objects 20 will appear from the detailed description and claims hereinafter.

I attain my objects by mounting a plurality of cup shaped strainers of different meshes, in a cage supported in a casing which it divides into approximately equal 25 chambers, one for intake of liquid and sediment and the other for clean gasoline. The coarsest mesh is on the intake side, and means are provided for removing sediment and for blowing or washing out the entire 30 casing and strainers when desired without taking the casing apart.

My invention is illustrated in the accompanying drawing in which:

Figure 1 is a side view of the device complete.

Figure 2 is an end view.

Figure 3 is a section thereof on the line 3—3 of Figure 2.

Figure 4 is a side view showing the cage 40 and strainers removed from the casing.

Referring to the drawings, 1 is a metal casing comprising a tubular body fitted with end caps 2 and 3, having central tapped openings closed by screw plugs 2^a and 3^a, 45 and lateral nipples 2^b and 3^b, for connection to discharge, and inlet pipes or tubing, respectively. In the side walls of the body are lugs 4 projecting inwardly to receive and hold the cage which carries the strainers 7 and 8. The cage is in two parts, one 50 part comprising a flanged ring or body 5 with arms 5^a supporting a lower ring 5^b for protecting the lower strainer; and the other part comprising a clamping ring 6 55 threaded into the flanged cage ring 5, and

carrying a bent up cross bar 6^a which serves to protect the upper strainer and also for engagement of fingers or a wrench to turn the clamping ring 6.

The two strainers 7 and 8 are cup shaped 60 with flanged edges, the flanges lying as shown upon the flange of the body ring 5, and being clamped thereto by ring 6. Interposed spring washers may be employed if desired. The lower strainer 8 is of 65 coarse mesh and the upper strainer 7 is of very fine mesh screening.

In operation the liquid to be strained, as gasoline, passes in through nipple 3^b as indicated by the arrow in Figure 3, thence 70 upwardly through the coarse strainer 8 and the fine mesh strainer 7, into the upper chamber and so out through nipple 2^b.

This strainer cannot become clogged, any matter that would ordinarily have that action being stopped at the lower or coarse mesh member 8, and the gasoline in the upper chamber being perfectly void of any dirt or sediment. The device as a whole 75 may be connected completely to a gasoline line, either pipe or copper tubing, in a very short time, and will operate with its axis either horizontal or vertical. In either case gravity assists in keeping the screen 8 clear 80 of sediment, which may be drawn off 85 through the lower opening in casing 1 by removing plug 3^a; or may be blown out thoroughly by removing both plugs.

I am aware that various changes and modifications may be made in this device 90 without departing from the spirit of my invention. For example, the strainers may be held in the cage by a groove in the inner face of the ring 6 and a spring ring or washer therein. Various other changes will 95 occur to those skilled in the art, and I wish it distinctly understood that I contemplate all such changes as fall fairly within the scope of the appended claims.

I claim:

1. A strainer for liquid supply lines comprising a cylindrical casing or body, bearing lugs therein projecting inwardly, an upper and a lower end cap fitted to the body, each having a central tapped opening closed by 100 a removable plug, and each having a lateral nipple for connection to discharge and to inlet pipe or tubing, respectively, and a cage centrally disposed in said body and supported on said lugs, said cage enclosing a pair of 105 110

- strainers and being in two parts, one part comprising a flanged ring or body with arms supporting a lower ring for protecting the lower strainer, and the other part comprising a clamping ring threaded into the flanged ring of the first part so as to clamp the strainers between them, and carrying a bent up cross bar serving to protect the upper strainer and also to turn the clamping ring. 10
2. A strainer as claimed in claim 1 in which the straining elements within the cage are in the form of flanged cups with their flanged edges placed together and clamped between the two parts of the cage. 15
3. A strainer as claimed in claim 1 in which the straining elements within the cage are in the form of flanged cups with their flanged edges placed together and clamped between the two parts of the cage and in which the said two cup shaped straining elements are of different mesh, the coarser mesh being on the inlet side. 20
4. A strainer for liquid supply lines comprising a hollow cylindrical casing or body, an upper and a lower end closure for said body, each having a lateral nipple for connection to a discharge and to an inlet pipe respectively, and a self contained unit strainer centrally supported in said body and comprising the following instrumentalities: A two part cage with means for connecting the two parts together, and a pair of straining elements in the form of opposite flanged cups with their flanged edges placed together and clamped between the two parts of said cage, said straining elements being of different mesh, the coarser mesh being placed on the inlet side of the body, and means carried by the cage surrounding and protecting said elements independently of the casing. 40
5. A strainer for liquid supply lines comprising a hollow cylindrical body divided intermediate of its ends, one portion being removable from the other, an inlet and an outlet opening in said portions respectively and a self contained strainer fitted within the end of one portion of the cylinder and comprising the following instrumentalities: 45 A pair of threaded rings, one screwing against a flange within the other, and two substantially semi-spherical or cup shaped strainners, one of fine mesh and the other of relatively coarse mesh, both having flanges around their open edges, said flanges being joined together and clamped between the meeting faces of the two rings when they are screwed together, together with an integral arch projecting above and beyond each 50 of said strainners and rigidly connected at its ends to opposite points on the corresponding ring, whereby a complete cage is formed to protect the strainners, and at the same time the projecting integral arches serve as mechanical means for manipulating the rings and the entire strainer structure regarded as a unit. 55
- In testimony whereof I hereunto affix my signature.

JOHN J. CASEY.
